CHUCKING MACHINE AND METHOD

Sven E. Green, Bristol, Conn., assignor to General Motors Corporation, Detroit, Mich., a corporation of Delaware

Application December 17, 1936, Serial No. 116,392

24 Claims. (Cl. 29—38)

This invention relates to chucking machines and methods and comprises all of the features of novelty herein disclosed. An object of the invention is to provide a machine and a method for completely machining all surfaces of a work-piece or of a pair of work-pieces at one handling of a single work blank. Another object is to provide suitable attachments for existing multi-spindle chucking machines such that more tools can be used and more operations can be performed. Another object is to produce a multi-spindle chucking machine which will reduce the expense of machining work-pieces as by eliminating the usual second handling of the piece. Still another object is to provide an improved method of machining work-pieces.

To these ends and also to improve generally upon devices and methods of this character, the invention consists in the various matters hereinafter described and claimed. In its broader aspects, the invention is not necessarily limited to the specific construction and steps selected for illustrative purposes in the accompanying drawings in which

25 Fig. 1 is a front elevation of the machine.
Fig. 2 is a right hand end elevation.

Fig. 3 is a cross sectional view taken in the plane of line 3—3 of Fig. 1.

30 Fig. 4 is a sectional view of an attachment taken about on the line 4—4 of Fig. 2.

Fig. 5 is an end view of a work spindle with its chuck removed.

Fig. 6 is an enlarged section of details at one end of a chuck operating rod.

35 Fig. 7 is a section on the line 7—7 of Fig. 4.
Fig. 8 is a front view partly in section of the keying device for the quill.

Fig. 9 is a sectional view taken on the line 9—9 of Fig. 2.

40 Fig. 10 is a sectional view taken on line 10—10 of Fig. 9.

Fig. 11 is a sectional view of a chuck operating cylinder and its controlling valve.

Fig. 12 is a front view of a tool and its carrier.

45 Fig. 13 is an enlarged end view of a portion of Fig. 12.

Fig. 14 is a perspective view of the turret chucks and associated apparatus.

50 Fig. 15 is a sectional view of the valves which control chucking and driving of the turret chucks.

Fig. 16 is a sectional view of a portion of the turret and associated fluid mechanism for operating the spindle clutches.

Fig. 17 is a front elevation of Fig. 16 with parts broken away and in section.

Figs. 18 to 24 are sectional views indicating the sequence of operations on a work-piece.

Figs. 25 to 31 are sectional views indicating 5 the sequence of operations to produce two finished articles from a single piece.

First outlining the general operation, a work blank such as a hollow sleeve, is chucked upon one of the rotary spindles of a carrier or turret 10 which is intermittently indexed to carry the piece successively to a plurality of stations for machining operations by suitable tools. When the piece returns to the loading station, it is released and transferred to an auxiliary chuck 15 which is advanced to grip the piece and then retreats to a working station for further treating the work by suitable auxiliary tools. Meanwhile a new piece is chucked at the loading station and is carried around to the successive stations. 20 This transfer of the piece to the auxiliary chuck enables the auxiliary tools to operate upon those surfaces which were previously grasped by the jaws of the turret chuck and so prevented access of tools to such surfaces. The transfer of 25 the piece not only effects economy by eliminating a subsequent handling and chucking of the piece on another machine but also contributes to accurate chucking and consequent concentricity of inner and outer surfaces because the transfer is mechanically effected. Further important economy results because two articles can be completed from a single work blank of slightly more 30 than double size to allow for severing and that double size blank can be forged or otherwise produced more economically than two single blanks. 35

The numeral 2 indicates a base supporting a main frame 4 in which is journaled for indexing movement a horizontal turret 6 carrying a series of individually rotatable work spindles 8. 40 In the illustrated construction, there are six spindles, each having chuck jaws 10 to grip a work-piece W, the chucks at the various stations being indicated by the letters A, B, C, D, E and F. The indexing of the turret 6, the driving 45 of the work spindles 8, and the actuation of the chuck jaws 10 is not per se a part of the present invention and may be controlled by any suitable mechanism such as indicated in the patents to Gridley et al. 2,055,434 and 2,055,435 granted Sept. 22, 1936.

A main tool carrier 12 of hexagonal form is provided on each face with slots 14 to receive suitable tools as required, the tool carrier being guided for reciprocating movement on a sup- 55

porting sleeve 16 projecting from the main frame 4. The tool carrier is fastened to a slide block 18 which slides on ways 20 supported by a cross member 22 which is bolted to pedestals 24 projecting upwardly from the base. The tool carrier 12 and the attached slide block 18 may be reciprocated by any suitable mechanism such as a cam-operated bar 26 projecting from the sleeve 16 and threaded at the outer end in nuts 28 confined to the slide block 18 by an end cap 30. The nuts 28 are formed externally as pinions so that, by inserting a suitable tool in a recess 32 of the end cap, initial adjustment of the tool carrier with respect to the turret can be effected in a manner well known.

Shafts 34 and 36 are rockably mounted in the pedestal 24 and usually carry arms 38 one of which is shown in Fig. 3 as provided with slots for T-bolts 40 for attachment of a tool holder. Ordinarily a tool mounted on the arm 38 operates on a work-piece secured to one of the turret carried work spindles at station A but, in the present machine, an extension arm 42 is bolted to the arm 38 and has slots for T-bolts 44 which clamp on a tool holder 46 with a tool 48 which operates near station F on a work-piece after such work-piece has been transferred to a supplemental chuck as will appear. Rockable and slidable shafts 50 and 52 project from the main frame 4 into bearing bosses 54 and 56, respectively, on a supplemental casing or frame 58 which is bolted to the cross member 22. The supplemental frame is rigidly braced from the main frame near the top by bracing bars 60 and 62 which project from the main frame and are secured by set screws 64 to bosses on the supplemental frame. Shafts 50 and 52 carry tool holders (not shown) with suitable tools for operating on the work in the turret-carried chucks as will appear.

In the supplemental casing or frame 58 (Figs. 1 to 4) are mounted an auxiliary work spindle and a quill with an actuating mechanism which effects rotation of the spindle, longitudinal shifting and locking of the quill, chucking and unchucking, there also being a cam-operated device (Fig. 9) to swing a supplemental tool for operation on the work after it is transferred to the auxiliary work spindle. For rotatably driving the auxiliary spindle, a power shaft 70 journalled in bearings 72 and 74 on the main frame is secured by a coupling 76 to a short shaft 18 which is journalled in bearings enclosed by cover plates 79 on a hollow standard 80 fastened to the supplemental frame 58. A sprocket wheel 82 is connected by a chain 84 with a sprocket wheel 86 keyed to a shaft 88 journalled in the supplemental frame upon ball bearings 90 and 92. The bearing 92 which is a double row ball bearing 60 has its inner race ring clamped on the shaft against the sprocket wheel 86 by a nut 94. The outer race ring is clamped against a shoulder in a flanged bearing housing 96 by a cap 98, the housing 96 being removably secured to the frame 58 by screws 100. The other bearing 90 has its inner race ring secured against a shoulder on the shaft by a pinion 102, the outer race ring being slidably mounted in a web 104. By removing the screws 100, the shaft, bearings, pinion and sprocket wheel are removable as a unit.

The pinion 102 drives a gear 106 journalled on a countershaft 108 and meshing with an elongated gear 110 which is keyed to a hollow spindle 112 and held from longitudinal movement on the spindle by a screw 114. The spindle is jour-

nalled for rotation in a quill 116 which is capable of sliding movement without rotation in bearings 118 and 120 in the supplemental frame, the quill being slotted at 122 to provide for sliding of the elongated gear 110 along the gear 106. Surrounding the slidable quill at the outer end of the bearing 118 is a felt seal retained by a recessed ring 123 and a cooperating washer. The spindle 112 is journalled near the chuck end in angular contact ball bearings 124 and 126 10 whose inner race rings are spaced apart by a sleeve 128 and locked against endwise movement on the spindle between a shoulder and a nut. The outer race rings are spaced by a sleeve 130 and are locked against endwise movement in the 15 quill between a shoulder and an end cap 132, the end cap cooperating with a companion cap 134 to form a felt holding seal engaging an enlargement of the spindle. Near the other end, the spindle is journalled in a double row ball bearing 136 whose outer race ring can slide in the quill and whose inner race ring is clamped against a washer engaging a shoulder by a tubular projection 138 threaded on the spindle and forming an extension of a chuck-operating 25 cylinder 140. Lubricant is retained and foreign matter excluded by a felt washer confined between a washer and an end cap 141 fastened to the end of the quill.

The cylinder 140 has a piston 142 connected 30 to a rod 144 which passes through a packing gland 146 in the spindle to thread into a draw bar 148 which operates a chuck. As best shown in Figs. 5 and 6, the draw bar has a flattened portion 150 engaged by a flattened area on the interior of a D-washer 152 which is secured in the spindle by a pin 154, thus compelling the draw bar to rotate with the spindle but allowing endwise movement. The front end of the spindle is enlarged and a chuck body 156 is secured 40 to it by screws 158, a key 160 being fastened to the enlarged end of the spindle by screws and entering a slot in the chuck body to insure against relative rotation. A detachable nose piece 162 has an enlarged portion threaded in the end of 45 the chuck body and has inclined cam surfaces for jaws or wedges 164 adapted to be expanded on the inside of a work-piece W which is located endwise by a locating ring 166 secured to the enlarged portion of the nose-piece. The 50 ring also prevents the wedges from dropping out when the work is released. To expand the wedges, a collar 168 is secured to the end of a bolt 170 which is keyed to the nose-piece and threaded in the front end of the draw bar 148. The bolt 170 is threaded in the draw bar when the nose-piece is threaded home. Endwise movement of the draw bar to the right expands the wedges to grip the work internally. Endwise movement in the opposite direction releases the wedges 60 which are forced back down the inclines of the nose-piece by plungers 172 engaged by a collar 174 surrounding the bolt 170 and backed up by check nuts. The work is pushed off the wedges by ejector pins 176 whose enlarged rear ends are 65 engaged by coil springs 178 housed in recesses of the collar 174.

The chuck spindle 112 and quill 116 are shown in Fig. 4 in the position they occupy while the work-piece W is being treated. The quill is normally locked against endwise movement by a locking bar 180 which enters a recess formed by wear plates 182 inserted in the quill. The locking bar is urged to locking position by a coil spring 184 which is backed up by a pilot screw 186 75

threaded for adjustment in the top of a housing 188 having a guiding wear plate 190 and a rear cover 192. Projecting from the locking bar through a slot in the rear cover is a cam roller 194 adapted for operation by a cam 196 fastened to the end of a rotary cam drum 198 which is keyed to a rotary shaft 200 and fastened to it by a set screw. The drum and shaft are retained endwise by thrust washers 201 engaging bosses on the frame 58. The cam 196 withdraws the locking bolt at the proper times to allow the quill and spindle to advance for the purpose of taking work pieces successively from the work spindles 8 when the latter reach the station F.

15 The quill 116 is held against rotation in its bearings 118 and 120 by a key 202 (Figs. 7 and 8) which enters an elongated slot 204 in the quill, the key being carried in a recess of a plate 205 attached to the frame 58 against a gasket 208. The quill is actuated longitudinally by a cam 210 formed by plates 212 and 214 attached to the periphery of the cam drum 198 and acting on a cam roller 216 rotatably mounted on a stud secured to a slide 220. The slide has limited movement in a dovetail way 222 formed in a block 224 which is fastened by screws 226 and by a pin 228 to the quill. The block has an end plate 230 against which the slide 220 is urged by a coil spring 232 reacting against an adjusting screw 234 carried by another end plate 236. The spring is to provide for yielding advance of the quill and will give whenever the empty auxiliary chuck 156 is forced against a work-piece in one of the chucks carried by the turret at 35 station F to transfer the piece from a turret chuck to the auxiliary chuck. The turret chucks and the auxiliary chuck rotate in the same direction and at the same speed to facilitate transfer.

40 The cylinder 140 travels with the spindle 112, and the operation of its chuck-operating piston is timed to release the work before the chuck takes on a new piece from a turret chuck, and to grip the new piece before the quill returns. A cylinder head 240 is secured to the outer end of the cylinder and has a cylindrical extension 242 with two spaced annular grooves 244 and 246. A port 248 leads from the groove 244 to the outer end of the cylinder. A central port 250 leading from the other groove communicates by passages 252 and 254 with the opposite end of the cylinder. A sleeve 258 surrounds the extension 242 and is retained by a plate 260. The sleeve has openings for two pipes 262 and 264 (Fig. 11) which communicate with the grooves 244 and 246 and with a valve casing 266. These pipes are flexible because the sleeve 258 travels longitudinally although it does not rotate with the cylinder head extension 242 which is journalled in it. The valve comprises spaced pistons 268 adapted to alternately put the pipes 262 and 264 in communication with a pressure line 270. There are also two spaced exhaust pipes 272 and 274 which alternately exhaust the fluid from the pipes 262 and 264. The valve stem has a yoke 276 to rotatably support a cam roller 278, the yoke having a lug 280 engaging an extension 282 on one of the valve caps to prevent rotation of the valve stem and thus hold the roller in line with a cam 284 which is adjustably secured on the end of the drum shaft 200. The valve casing is mounted (Figs. 1 and 2) on one end of the supplemental frame 58 in such a position that the cam roller will engage the cam. A coil spring 286 is connected to the yoke

276 and to an anchoring stud 288 so that the cam roller is held against the cam.

Another instrumentality operated by cams on the cam drum 198 is a sliding and swinging shaft carrying a supplemental tool to operate on each work-piece after it has been transferred to the auxiliary spindle. (See Figs. 3, 9 and 10.) The shaft 290 is journalled in bosses 292, 294 and 296 of the supplemental frame. Its endwise movement is controlled by a cam slot formed by cam plates 298 and 300 on the periphery of the drum and straddling a cam roller 302 journalled on a stud projecting from a block 304. The block is loose on the shaft although confined between collars 306 pinned to the shaft. The block is held from turning with the shaft by an extension 308 which is guided on a rod 310 fixed in the supplemental frame. The cam roller is thus held from swinging out of the cam slot when the shaft 290 is swung.

Rocking or swinging movement of the shaft 290 is controlled by an arm 312 having its hub provided with a key 314 entering an elongated slot 316 in the shaft. The arm carries a cam roller 318 arranged for actuation by a segmental cam plate 320 (Figs. 3 and 4) attached to a ring 321 fastened around an extension at the end of the cam drum 198, a coil spring 322 anchored to the arm and to the frame urging the roller against the cam plate. To insure swinging of the arm in case the spring fails, another segmental and outside cam plate 324 is attached to the ring 321. A tool carrying arm 326 is clamped to the outer end of the shaft 290. Adjustably secured to the arm by screws 327 is a tool holder 328 with spaced ribs 330 (Fig. 13) having opposed adjusting screws 332 straddling a lug 334 on a ratchet 336. A tool 338 has a companion ratchet to engage the ratchet 336 and is secured to the tool holder by a clamping bolt 340. Coarse angular adjustment of the tool is provided by the ratchet faces and fine adjustment by the screws 332. The tool operates on the work carried by the auxiliary chuck 156. Its inward swinging movement towards the work is limited by an abutment plate 342 (Fig. 3) mounted on a bracket 343 secured to the frame 58 and engaged by an arcuate locating plate 344 adjustably secured in an arcuate guide in the arm 326 by a clamping screw 346. The arcuate plate 344 is accurately located in its guide by a screw 348 threaded in the arm and adapted to abut against the end of the arcuate plate.

The cam drum 198 carries a gear 350 (Fig. 4) secured to it by the same screws which secure the ring 321. The gear is driven by a gear 352 keyed to a short shaft 354 which is journalled in a boss 356 of the supplemental frame 58. At the outside of the frame is a collar 358 to hold the shaft from endwise movement. The shaft is connected by a coupling 360 to a short shaft 362 (Fig. 1) having a similar coupling 364 to secure it to a timing shaft 366 which projects from the main frame. One of the collars of coupling 360 has arcuate slots 368 for clamping screws whereby timing can be varied.

Referring to Figs. 14 to 17, each work spindle 8 on the turret 6 is provided with a grooved clutch collar 370 urged to clutching position by a coil spring 372, so that the spindles when in working positions will be rotatably driven from any suitable power source. A fork 374 engaging each clutch collar is guided on a rod 376 carried by projecting flanges 378 on the turret 6. Each fork for each spindle clutch has a cam roller 380 adapted for actuation by a cam 382 on a slide 384.

which is guided by bars 386 and 388 projecting from the main frame and carrying coil springs 390 which urge the slide to a retracted position. The slide is adjustably secured by nuts to the threaded end of a piston rod 392 having a piston 394 in a cylinder 396. The above mentioned springs urge the piston against an adjustable stop screw 398 but the piston can be advanced to throw out the clutch. To lock the clutch out temporarily, as when a new piece of work is being chucked on the work spindle, a collar 400 on the piston rod is adapted to ride behind a latch hook 402 on an arm which is pivoted at 404 on a bracket 406 projecting from the cylinder.

15 Fluid under pressure can be admitted behind the piston through a passage 408 having an adjustable throttle valve 410, the passage communicating with a chamber 412 containing a slidable piston valve 414 with two spaced pistons. Fluid is admitted between the pistons from a pressure line 416 and will communicate with the passage 408 when the valve 414 is slid to the left in Fig. 15. Normally the passage 408 is open to an exhaust line 418. The valve has a projecting stem 420 with two annular grooves adapted to be engaged alternately by a spring pressed ball detent 421 to hold the valve in its extreme positions. A link 422 connects the valve stem to an arm 424 pinned to a rock shaft 426 which projects through the frame and carries an actuating handle 428. By rocking the handle, the piston valve 414 can be slid to the left to advance the clutch operating piston 394 and throw out the spindle clutch to permit chucking and it can be shifted back to the right to let the piston 394 come back under spring pressure to throw in the spindle clutch and start spindle rotation after chucking.

20 For successively controlling the chucks on the work spindles 8 as the latter reach the loading station F, there is a second valve chamber 430 with a piston valve 432 comprising spaced pistons in communication with the pressure line 416, the chamber 430 having two exhaust lines 434 and 436 for alternately exhausting fluid from ports 438 and 440 which lead to a distributor (not shown) having fluid connections with cylinders on all the spindles. Each cylinder 442 has a piston 444 connected to the draw rod 446 of the respective chuck. Patent to Gridley 2,055,435 above mentioned has 25 a somewhat similar fluid system. The piston valve 432 has a stem 448 provided with grooves adapted to be engaged alternately by a spring pressed ball detent 450 to hold the valve in its extreme positions. A link 452 connects the valve stem to an arm 454 of a lever which is secured to a sleeve 456 which serves as a journal for shaft 426 and is rockably mounted in the frame and operated by a handle 458. In the position shown in Fig. 15, pressure fluid goes through the port 438 and thence to the chucking cylinder 442 to hold the chuck jaws closed on the work. By swinging the lever, the piston valve 432 can be shifted to the left to put the port 440 in communication with the pressure line 416 to thereby operate the chucking piston to open the chuck but the piston valve 432 is preferably operated automatically in this direction. For this purpose, a lever arm 460 is connected by a link 462 to a bell crank lever 464 which is connected by a link 466 with a second bell crank lever 468 carrying a cam roller 470 in the path of a cam 472 on a cam shaft 474. The cam is timed to actuate the valve and open each chuck after such chuck has reached the loading station F and before its spindle has been stopped 30 from rotating by the throwing out of its clutch.

On the stem 448 is a collar 476 which normally engages an inclined cam surface on an arm 478 which is a part of the same lever which carries the latch hook 402. Whenever the sleeve 456 is swung in a direction to shift the piston valve 432 to the left, the collar 476 releases the arm 478 so that the latch hook is ready to drop down behind the other collar 400 as soon as the clutch-controlling piston rod 392 is advanced, thus affording a means to insure the holding out of the work 35 spindle clutch 378 until a work-piece is chucked.

Figs. 18 to 24 inclusive indicate operations which can be carried out by the machine. The rough work is indicated as an internally-ribbed sleeve to be made into a double row, outer race 15 ring, and each piece is inserted in the chuck jaws 10 of one of the turret spindles 8 as such spindle reaches the loading station F. The turret then indexes to carry the piece to station A for operation by tools, such as a turning tool 480 shiftable 20 axially along the outside of the work, a rough boring tool 482 shiftable axially, and a facing tool 484 swinging radially. At station B, there may be a further turning operation by a tool 486 and a further boring operation and a rounding of 25 corners by a tool 488. At station C, a tool 490 moves axially and radially to form a rough ball race and an internal rounded corner while a tool 492 faces the end and forms an external rounded corner. At station D, a boring tool 494 cuts ball 30 races and finishes the inside corners while a tool 496 faces and finishes the outside corner. At station E, a boring tool 498 finishes the ball races. At station F, the piece is released from the turret spindle jaws 10 and transferred to the chuck 156 35 on the supplemental spindle whose quill retreats to a working and locked position where the tool 338 above mentioned turns the exterior surface in the region where the chuck jaws 10 were previously gripping the piece. At this same position, the tool 48 faces the now accessible end and rounds the corner. Thus all surfaces of the piece are finished at a single handling by one machine. When the piece is thus transferred to the supplemental chuck, a new piece is inserted in the chuck 45 jaws at station F ready to be indexed to station A.

Figs. 25 to 31 inclusive illustrate how two articles can be completed from a single piece W1 at a single handling by one machine. The piece may be a plain sleeve loaded at station F and first 50 operated upon at station A by a turning tool 500, by a boring tool 502, and by a recess forming tool 504. At station B, another turning tool 506 operates on the exterior and another boring tool 508 operates on the interior. At station C, there is 55 indicated a recess forming tool 510, a facing tool 512, and a boring tool 514. At station D there is a tool 516 for facing one end and rounding the corner while a boring tool 518 completes a pair of raceways. At station E, a cut-off tool 520 60 severs a completely machined single row race ring W2 from the piece W1. The remainder of the piece continues to station F where it is transferred to the supplementary chuck 156 and treated by the tools 338 and 48 to complete another race 65 ring.

The tools above referred to are merely illustrative of suitable tools which can be used as required. They show that a work-piece can be treated on some surfaces when in the turret 70 chucks, followed by transfer to a supplemental chuck for operation on surfaces previously engaged by the jaws of the turret chucks. While the turret chucks are shown as gripping the exterior of the work and the supplemental chuck 75

is shown as gripping the interior, it will be apparent that this engagement may be reversed or that both chucks may be of the internally expanding or exterior gripping types.

5 In operation, assuming work-pieces W are held in all of the work chucks A to F inclusive on the turret and that the work-piece in the chuck F has been operated upon by all of the usual tools pertaining to the turret stations, such work-piece 10 finally returns to the loading station F. It is still in the chuck F and its spindle is rotating but no work can be performed on those surfaces which are engaged by the chuck jaws 10 as long as the piece is held by them. At this time, the 15 quill 116 of Fig. 4 carrying the supplemental spindle 112 becomes unlocked by the cam 180 and is advanced towards and in line with station F by the cam 210. Its spindle rotates at the same speed as the turret chuck F and turns in 20 the same direction. While the rotating piece is still gripped and centered by the turret chuck, the supplemental chuck wedges 164 are expanded to grip the piece internally under control of the piston 142, valve 266 and cam 234. The cam 25 412 of Fig. 17 now shifts the piston valve 432 to the left and the chucking piston 444 of the turret chuck is operated to release the work-piece so it can be carried away by the supplemental chuck when the quill returns to its outward, 30 locked position where work is to be performed by the tools 48 and 338 on the hitherto inaccessible work surfaces. The turret spindle at the loading station F is still rotating. Handle 428 is now rocked to move the other piston valve 414 to the left thereby advancing the clutch controlling piston 394 to release the turret spindle clutch 378 and stop the rotation of its spindle. The clutch is held out temporarily by reason 35 of the safety latch hook 402 dropping down behind the collar 400. A new piece is now put in the chuck F. Next, the lever 450 is swung manually in the opposite direction and the piston valve 432 shifts to the right to cause the turret chuck piston 444 to operate its chuck to grip 40 the new piece. The collar 476 raises the latch hook 402 and frees the clutch piston 394 although the latter is still held temporarily in its advanced position by fluid pressure from the line 416. Next the other handle 428 is swung back 45 to slide the other piston valve 414 to the right to thereby let the clutch piston 394 return by spring pressure and throw in the clutch to start rotation of the turret spindle. Thereafter the turret indexes the spindle to the A position for 50 operation by the tools and advances all of the other spindles one station. Meanwhile the work transferred to the supplemental chuck 156 is operated upon by the two tools 48 and 338 and the work is finally released from the machine in 55 a completely machined condition on all surfaces.

I claim:

1. In a machine of the character described, a frame, a quill mounted to slide endwise in the frame, a spindle journalled for rotation in the quill and having a chuck, means for locking the quill in retracted position, a cam for retracting the locking means, and a cam for sliding the quill to advance the chuck to a loading position; substantially as described.
2. In a machine of the character described, a frame, a quill mounted to slide endwise in the frame, a spindle journalled for rotation in the quill and having a chuck, means for sliding the quill to advance the chuck to a loading position, and a cylinder and piston unit shiftable

with the quill for operating the chuck; substantially as described.

3. In a machine of the character described, a frame, a quill mounted to slide endwise in the frame, a spindle journalled for rotation in the quill and having a chuck, means for sliding the quill to advance the chuck to a loading station, a cylinder and piston unit shiftable with the quill for operating the chuck, a valve controlling said unit, and a cam for operating the valve; substantially as described.

4. In a machine of the character described, a frame, a quill mounted to slide endwise in the frame, a spindle journalled for rotation in the quill and having a chuck, a cylinder and piston unit shiftable with the quill for operating the chuck, a valve controlling said unit, a cam for operating the valve, and a cam for sliding the quill to advance the chuck to a loading position; substantially as described.

5. In a machine of the character described, a frame, a quill mounted to slide endwise in the frame, a spindle journalled for rotation in the quill and having a chuck, means for locking the quill in one position, a cam for retracting the locking means, a cylinder and piston unit shiftable with the quill for operating the chuck, a cam for controlling said unit, and a cam for sliding the quill to advance the chuck to a loading position; substantially as described.

6. In a machine of the character described, a frame, a quill mounted to slide endwise in the frame, a spindle journalled for rotation in the quill and having a chuck, a gear within the quill and secured to the spindle, a driven gear mounted on the frame and projecting through an opening in the quill to drive the spindle gear, one of the gears being elongated, and means for sliding the quill to advance the chuck to a loading position; substantially as described.

7. In a machine of the character described, a spindle journalled for rotation and having a chuck, a second chuck in alignment with the first chuck and adapted to grip or release a work-piece, means for advancing the first chuck towards the second one, said advancing means having a yieldable member to provide lost motion when the first chuck engages the work-piece; substantially as described.

8. In a machine of the character described, a spindle journalled for rotation and having a chuck, a second chuck in alignment with the first chuck and adapted to grip or release a work-piece, means for advancing the first chuck towards the second one, a rotatable cylinder and piston unit connected with the spindle to advance therewith, the cylinder and piston also being relatively movable for operating the first chuck, and means for supplying operating fluid to said unit; substantially as described.

9. In a machine of the character described, a spindle journalled for rotation and having a chuck, a rotatable cylinder and piston unit connected to the spindle for operating the chuck, and means for axially reciprocating the spindle and unit; substantially as described.

10. In a machine of the character described, a turret having work spindles, each spindle having a clutch to control rotation and a chuck to grip or release a work-piece, a piston and cylinder unit to operate each chuck, a piston and cylinder unit to operate all the clutches in sequence, a valve to control the chuck operating pistons, a valve to control the clutch

- operating piston, means for operating the chuck controlling valve to release a work-piece, means for operating the clutch controlling valve to throw out a spindle clutch, means for latching out the spindle clutch while loading the chuck, means for operating the chuck controlling valve to cause gripping of a new piece and release of the latch, and means for operating the clutch controlling valve to control renewed driving of the spindle; substantially as described.
11. In a machine of the character described, a turret having work spindles, each spindle having a clutch to control rotation and a chuck to grip or release a work-piece, a piston and cylinder unit to operate each chuck, a piston and cylinder unit to operate all the clutches in sequence, a latch, valves to control the chuck operating pistons and the clutch operating piston, and means to operate each valve to throw out and latch a clutch until a new piece is gripped in the chuck; substantially as described.
12. In a machine of the character described, a turret having work spindles, each spindle having a clutch to control rotation and a chuck to grip or release a work-piece, a piston and cylinder unit to operate each chuck, a piston and cylinder unit to operate all the clutches in sequence, a valve to control the chuck operating piston, a valve to control the clutch operating piston, means to operate the clutch controlling valve to throw out a clutch and latch it, and means to operate the chuck controlling valve to grip a new piece and release the latch; substantially as described.
13. In a machine of the character described, a work spindle having a clutch to control rotation and a chuck to grip or release a work-piece, a piston and cylinder unit to operate the chuck, a piston and cylinder unit to operate the clutch, a latch for the clutch, a valve to control the chuck operating piston, a valve to control the clutch operating piston, means to operate the clutch controlling valve to throw out the clutch and latch it, and means to operate the chuck controlling valve to grip a new piece and release the latch; substantially as described.
14. In a machine of the character described, a work spindle having a clutch to control rotation and a chuck to grip or release a work-piece, a piston and cylinder unit to operate the clutch, a latch for the clutch, a valve to control the unit, means for shifting the valve to throw out the clutch and latch it, and chuck controlling means for releasing the latch; substantially as described.
15. In a machine of the character described, a work spindle having a clutch to control rotation and a chuck to grip or release a work-piece, a piston and cylinder unit to operate the chuck, a valve to control the unit, means to throw out the clutch, a latch for the clutch, and means for shifting the valve to operate the chuck and release the latch; substantially as described.
16. The method of machining a pair of articles from a single piece of substantially double size with an extra length for severing and separating the articles, which consists in chucking the double size piece by gripping only a portion pertaining to the rear end of one article to leave exposed for machining all the portions pertaining to the other article plus a portion of said one article, machining said exposed portions pertaining to said other article and a portion

of said one article, rechucking by gripping another portion of the double size piece to leave exposed that portion at the rear end of said one article which was previously gripped, and machining said previously gripped portion; substantially as described. 5

17. The method of chucking and machining a pair of articles from a single piece of substantially double size with an extra length for severing and separating the articles, which consists in chucking the double size piece by gripping only one end portion thereof to leave all other portions exposed, machining all exposed portions pertaining to one article, rechucking the piece by gripping a machined portion to expose said previously gripped portion, and machining the newly exposed, previously gripped portion; substantially as described. 10 15

18. In a machine for chucking and completely machining a pair of articles from a single piece of substantially double size with an extra length for cutting off, a chuck for gripping only one end portion of the double size piece to leave all other portions exposed, means for machining substantially all exposed portions, means for cutting off some of said machined portion to release one completed article from the piece held in the chuck, a second chuck for gripping a machined portion of the remaining part of the piece while the previously gripped portion remains gripped by the first chuck, means for operating the first chuck to release its hold on the piece, and means for machining the newly exposed previously gripped portion to complete a second article; substantially as described. 20 25 30 35

19. In a machine for chucking and machining a pair of articles from a single piece of substantially double size with an extra length for cutting off, a chuck for gripping only one end portion of the double size piece, means for machining the exposed portion, means for cutting off said machined portion to produce one article, a second chuck adapted to hold the remaining part by gripping a portion other than that previously gripped and before said previously gripped portion is released, and means for machining the previously gripped portion to produce a second article; substantially as described. 40 45 50

20. In a machine for chucking and machining a pair of hollow articles from a single sleeve of substantially double size with an extra length for cutting off, a chuck for gripping only one end portion of the double size sleeve, means for machining exposed portion of the sleeve, means for cutting off and releasing the machined portion to produce a finished article, a second chuck for gripping a projecting surface of the portion remaining in the first chuck, means for thereafter causing the first chuck to release the piece, and means for machining the previously gripped and newly exposed portion of the piece to produce a second article; substantially as described. 55 60 65

21. In a machine for chucking and machining a pair of articles from a single sleeve of substantially double size with an extra length for cutting off, a chuck for gripping a portion of the exterior surface of the sleeve, means for machining the exposed portion of the exterior surface and the interior surface, means for cutting off the sleeve at an intermediate area to produce one article, a second chuck for gripping the interior surface of the remaining portion of the sleeve before the exterior surface thereof is released, and means for machining the newly exposed ex- 70 75

terior portion of the sleeve to produce a second article; substantially as described.

22. In a machine for chucking and machining all surfaces of a hollow work-piece, a chuck for gripping one peripheral surface of the piece, means for machining the exposed portion of the peripheral surface and the opposite peripheral surface, a second chuck adapted to grip said opposite peripheral surface while the piece remains in the original position and is still gripped by said one peripheral surface, means for causing the first mentioned chuck to release said one peripheral surface, and means for machining the newly exposed portion of the piece; substantially as described.

23. In a machine for chucking and machining a pair of articles from a single piece of substantially double size with an extra length for severing and separating the articles, a chuck adapted to grip only a portion pertaining to the rear end of a first article to thereby leave exposed all the portions pertaining to the second article plus

a portion pertaining to the first article, means for machining the exposed portions pertaining to both articles, a second chuck adapted to grip another portion of the double size piece to leave exposed that previously gripped portion at the rear end of the first article, and means for machining said previously gripped portion; substantially as described.

24. In a machine for chucking and machining a pair of articles from a single piece of substantially double size with an extra length for severing and separating the articles, a chuck adapted to grip only one end portion of the double size piece to leave all other portions exposed, means for machining all exposed portions pertaining to one article, a second chuck adapted to grip a machined portion to expose the previously gripped portion, and means for machining the newly exposed previously gripped portion to complete a second article; substantially as described.

SVEN E. GREEN.
